UNITED STATES PATENT OFFICE.

WILLIAM E. MORELAND, OF UNION CITY, GEORGIA.

BUCKLE.

1,272,296.

Specification of Letters Patent.

Patented July 9, 1918.

Application filed April 21, 1917. Serial No. 163,648.

To all whom it may concern:

Be it known that I, WILLIAM E. MORELAND, a citizen of the United States, residing at Union City, in the county of Campbell and State of Georgia, have invented new and useful Improvements in Buckles, of which the following is a specification.

This invention relates to buckles or strap fastening devices and comprehends the provision of a buckle having a main frame, a pivot bar extending across said frame and a substantially U shaped member pivotally connected to the pivot bar and adapted to clamp a strap or other flexible member against one end of the main frame.

One of the objects of the invention is to provide a buckle, capable of various modifications, which may be cheaply manufactured, which is very efficient and which may be easily operated.

Another object of the invention is to generally improve buckles of this nature to render them more practical, useful and commercially desirable.

With these and other objects in view as will become more apparent as the description proceeds, the invention consists in certain novel features of construction, combination and arrangements of parts as will be hereinafter fully described, illustrated and claimed.

In the drawings,

Figure 1 is a perspective view showing the use of my improved buckle as a strap fastening device to secure a number of books together.

Fig. 2 is a perspective view of the buckle detached from the strap.

Fig. 3 is a plan view showing the buckle connecting two end portions of a strap.

Fig. 4 is a longitudinal sectional view on the plane of line 4-4 of Fig. 3.

Fig. 5 is a perspective view of a modified or double buckle showing the same in use,

Fig. 6 is a perspective view of the modified buckle detached from its strap.

Referring in detail to the drawings by numerals, 1 designates as an entirety the main frame having side bars 2, 3 and end bars 4, 5. The side bar 3 is formed in two sections and the longer section is extended transversely of the frame and secured to the side bar 2 thus providing a pivot bar 6. The short section of the bar 3 is attached

to the long section by being twisted about the pivot bar adjacent to the long section.

The end bar 5 acts in the capacity of a binding or resistance element and co-operates with a clamping frame 7 to bind against a strap or other flexible member. The clamping member 7 is substantially U shaped having the central clamping or binding bar 8 and the arms 9 which are pivotally connected at their terminals to the pivot bar 6 by being twisted thereabout. The clamping bar 8 is somewhat longer than the width of the main frame, thus preventing the clamping member swinging through the frame. The arms 9 are bent inwardly across the side bars of the main frame and are then extended substantially parallel to each other to their points of connection with the pivot bar. This construction gives to the clamping member a four point contact with the main frame and therefore it is able to resist most any strain which may be placed upon it by the strap 10.

For the purpose of manipulating the clamping frame so as to easily release it from clamping engagement with the strap 10, I provide a bail or handle 11 which is pivotally secured at its ends to the clamping bar 8 by being bent thereabout as shown.

In using this buckle as a fastening device for a book strap, one end of the strap is permanently secured to the end bar 4 of the main frame and the strap may be clamped about a pile of books by passing the same around the books through the frame 4 around the clamping bar 8 and under the binding bar 5. The slack may be taken up by pulling on the end of the strap and the strap is prevented from loosening by the clamping action exerted thereon by the bars 5 and 8. When it is desired to loosen the strap, it is only necessary to pull upwardly on the bail or handle 11 which will swing the clamping member away from the resistance bar 5.

In Fig. 5 I have shown what may be termed a double buckle including a pair of rectangular frames 12 and 13 which are secured together at right angles to each other and to one side of their transverse centers. The frame 12 comprises side bars 14, 15 and end bars 16, 17; and the frame 13 comprises side bars 18, 19 and end bars 20, 21. The side bar 19 of the frame 13 forms a pivot bar for the frame 12 and a substan-

tially U shaped clamping member 22 is pivotally secured at its ends to the bar 19 between the frame bars 14 and 15. The clamping bar 23 of the clamping member extends 5 across the side bars of the frame 12 and the arms of the clamping member are bent inwardly from the ends of the clamping bar 23 across the frame bars as shown.

The side bar 15 of the frame 12 forms a 10 pivot bar for the frame 20 and a clamping member 24 similar to the clamping member 23 pivotally secured at its ends to the bar 15 between the side bars 18 and 19 of the frame 13.

15 In using this double buckle, a belt or other flexible member 25 is secured to one of the rectangular frames as shown, and is preferably passed around the object to be strapped through the other end of the frame 20 to which it is connected, over the clamping bar 24 and back through the frame as shown.

A right angular turn is then made by passing the strap over the bar 18 and under the bar 16. The strap is next carried around the 25 object to be strapped and passed through the frame 12, around the clamping bar 23 and back through the frame as shown. Slack may be taken up by pulling on the free end of the strap. Each of the clamping members is provided with a bail or handle 30 26 to facilitate the release of the strap.

From the foregoing description taken in

connection with the accompanying drawings, it will be evident that I have provided a very simple and practical buckle which 35 may be used in various ways and which will securely clamp onto a flexible member such as a strap.

While I have shown and described the preferred embodiments of my invention, it 40 will be clearly understood that I do not wish to be limited to this construction, but may make such changes as will fall within the scope and spirit of the invention as claimed.

What I claim is:

45 A buckle comprising a main frame, a pivot bar extending transversely across and secured to said main frame, a U-shaped clamping member having the ends of its arms pivotally secured to the pivot bar between the side bars of the main frame, the base of the U-shaped clamping member extending transversely across and beyond the side bars of the main frame adjacent the opposite end of said frame to define a 50 clamping bar, inwardly extending portions connecting the extremity of the clamping bar with the arms of the clamping member to provide additional bearing against the main frame and a bail secured to the clamping bar at a point beyond the side bars of the main frame.

55 In testimony whereof I affix my signature.

WILLIAM E. MORELAND.
